UNITED STATES PATENT OFFICE

2,549,222

INNER TUBE TESTER

August Moebes, Vallejo, Calif.

Application June 10, 1947, Serial No. 753,680

2 Claims. (Cl. 73—49)

1

The present invention relates to improvements in an inner tube tester; and it consists of the combinations, constructions and arrangement of parts hereinafter described and claimed.

An object of my invention is to provide a device of the character described that will support an inner tube in substantially upright position, and which will allow the inner tube to be be rotated circumferentially in a body of water in which the lower portion of the tube is submerged. After this portion is once placed in the water, the tube may be turned to allow its inspection. As the tube is rotated, ripples will not form on the water, since the tube is turned circumferentially. This will facilitate the inspection of the tube for leaks inasmuch as the repairman will have a clear view of the submerged portion of the tube.

More specifically described, I provide a vertically-mounted standard having a rotatable reel adjustably carried thereby. The reel may be depressed so as to submerge the lower portion of the tube in a tank of water. After the repairman has completed his inspection and marked any leaks that he may have discovered, the reel may be raised again to remove the tube from the tank.

A still further object is to provide clamping means for automatically holding the tube-carrying reel in any position to which it has been adjusted on the standard.

Another object of my invention is to provide an inner tube tester that is simple in construction, durable and efficient for the purpose intended, and which may be manufactured at a relatively low cost.

Other objects and advantages will appear as the specification continues, and the novel features will be set forth in the claims hereunto appended.

For a better understanding of my invention, reference should be had to the accompanying drawing, forming part of this application, in which:

Figure 1 is a perspective view of my inner tube tester, looking from the front thereof;

Figures 2 and 3 are vertical transverse sections taken along the line II—II and III—III, respectively, of Figure 1; and

Figure 4 is an isometric view of a slide and one of the clamping plates that I employ, a portion of the standard being shown in dot-dash lines.

While I have shown only the preferred form of my invention, it should be understood that various changes, or modifications, may be made within the scope of the annexed claims without departing from the spirit thereof.

In carrying my invention into practice, I provide a reel indicated generally at A on which an inner tube B is adapted to be mounted in upright position. A vertically-disposed standard C

2

constitutes a support for the reel. The latter may be depressed relative to the standard so as to submerge the lower portion b of the inner tube in a body of water D contained in a tank E. After this portion of the tube is submerged, the reel may be rotated for moving the tube circumferentially through the water.

It will be noted that the reel A includes radially-extending spokes 1, the inner ends of which are 10 welded or otherwise secured to a disc 2. In turn, the disc is fixed to a hub 3 by welding 4, or other suitable fastening means. The outer end of each spoke is curved to provide an arm 5 that is shaped to embrace the inner periphery of the tube B in 15 the manner shown in Figure 2. When the tube is inflated, it is supported vertically on the arms 5 (see Figures 1 and 2).

The standard C has a slide 6 movable lengthwise thereof and held against rotation with respect thereto. The slide and standard may be fashioned from tubing that is square in cross section, as illustrated in Figure 4, and this arrangement will prevent the slide from turning on the standard. The slide has a trunnion 6a on which 20 the hub 3 is rotatably mounted. The reel B may be rotated circumferentially during the testing operation.

In Figure 2, I show the standard C as being 25 welded at 7 to a horizontally disposed base plate 8. A hook-like clamp 9 is anchored to the standard and engages over the top of the tank E so as to aid in holding the standard in upright position.

Any suitable means may be provided for supporting the base plate 8 and the tank E so as to present the tank and the inner tube at a convenient working height for a repairman. For this purpose, I have disclosed a table indicated generally at F. The base plate 8 is anchored to 30 the horizontal rails 10 of the table. Saddle-like blocks 11 may be inserted between the base plate and the tank, as shown in Figure 1, in order to give a firm foundation for the tank.

The inner tube B is moveable into the water 35 D when the slide 6 is depressed on the standard, and is moveable out of the water when the slide is raised.

In order to automatically hold the slide in the position to which it is adjusted by the repairman, I provide clamping plates G1 and G2. The plate G1 is arranged above the slide, while the plate G2 is arranged below the slide. Both of these clamping plates are fashioned with apertures 12 that loosely receive the standard. A 40 spring 14 interconnects the clamping plates and urges these plates into angular positions relative to the standard so as to grip the latter.

Referring now to Figure 3, it is obvious that 45 the slide 6 is moveable downwardly along the standard C when the upper clamping plate G1

is manually swung into horizontal position (as indicated in dot-dash lines) to free its grip on the standard. Likewise the slide is moveable upwardly along the standard when the lower clamping plate G2 is manually swung into horizontal position to free its grip on the standard.

Lugs 15 extend from the slide at the top and bottom thereof (see Figures 3 and 4). The clamping plates G1 and G2 are provided with fingers 16 which engage with the lug adjacent thereto. The lugs and fingers provide hinge connections between the clamping plates and the slide. The lugs 15 and fingers 16 may be omitted when a relatively strong spring 14 is employed. In this case, the clamping plates G1 and G2 merely rock about the upper and lower edges 17 and 18, respectively, of the slide.

Having thus described the various parts of my inner tube tester, the use thereof is summarized briefly as follows:

The repairman places the inner tube B over the curved arms 5 of the rotatable reel A, as clearly disclosed in Figures 1 and 2. The upper clamping plate G1 is moved into horizontal position so as to free its grip on the standard C. At this time, the slide is moved downwardly along the standard until the lower portion b of the inner tube is submerged in the water D to the desired depth.

As soon as the water in the tank E reaches a quiescent state, the repairman starts turning the inner tube and watches for air bubbles to appear. Any leaks discovered in the inner tube are suitably marked, as for instance with an indelible pencil. It is not necessary for the repairman to place his hands in the water D.

When the lower portion of the tube is once submerged to the desired depth, no further ripples will occur on the water. This is due to the smooth outer surface of the inner tube being advanced into the water as the tube is rotated. Thus the repairman has unobstructed observation of the tube being tested. Any dirt in the bottom of the tank will not be disturbed as the tube is rotated. The water runs off the inner tube and drains back into the tank.

After the inner tube has been tested and the leaks marked, the repairman swings the lower clamping plate G2 into horizontal position to free its grip on the standard. Thereupon, the slide 6 is raised along the standard until the inner tube B clears the top of the tank.

It is natural for the workman to press downwardly on the clamping plate G1 when pushing the inner tube into the water, and to lift upwardly on the clamping plate G2 when raising the

inner tube out of the water. The clamping plates will hold the slide in any position to which it is adjusted relative to the standard.

An operator in using his hands for submerging an inner tube in a tank is inclined to hurry his operation due to the fact that he wants to get his hands out of the water as soon as possible. This leads to carelessness in finding slow leaks because the movement of the tube into and out of the water agitates the water and creates bubbles and eddy currents that makes it difficult to discover a slow leak.

I claim:

1. An inner tube tester comprising a tank for holding water, an upright standard mounted adjacent said tank and extending thereabove, a rotatably mounted reel disposed over the tank for supporting an inner tube in substantially an upright position, a reel-supporting member slidably carried by the standard and mounting said reel, and clamping means mounted on said reel-supporting member cooperating with said standard to automatically maintain the reel and its supporting member in selected positions along the length of the standard.

2. An inner tube-tester comprising a tank for holding water, an upright standard mounted adjacent said tank and extending thereabove, said standard having a supporting member slidably mounted thereon, a reel rotatably mounted on said supporting member for supporting an inner tube in substantially an upright position over said tank, and spring-actuated clamp means mounted on said supporting member cooperating with said standard to secure said supporting member and reel to the standard at any selected position along the length of the standard.

AUGUST MOEBES.
